Primary Examiner — Austin Murphy(74) *Attorney, Agent, or Firm* — MORGAN, LEWIS & BOCKIUS LLP(57) **CLAIM**

The ornamental design for an electronic device, as shown and described.

DESCRIPTION

FIG. 1 is a perspective view of an embodiment of our new design of an electronic device;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The oblique lines represent a transparent or translucent surface.

The broken lines showing elements in the Figures are for illustrative purposes only and form no part of the claimed design.

1 Claim, 7 Drawing Sheets(56)
